UNITED STATES PATENT OFFICE

140,383

DESIGN FOR A FLAT BRIM HOLDER FOR SPIRAL STITCHING OF HATS

Isidore Klainbard, New York, N. Y.

Application November 29, 1944, Serial No. 116,605

Term of patent 3½ years

(Cl. D70—2)

To all whom it may concern:

Be it known that I, Isidore Klainbard, a citizen of the United States of America, residing in New York, county of New York, and State of New York, have invented a new, original, and ornamental Design for a Flat Brim Holder for Spiral Stitching of Hats, of which the following is a specification, reference being made to the accompanying drawing, forming a part thereof, in which

Figure 1 is a top plan view of a flat brim holder for spiral stitching of hats showing my new design.

Figure 2 is a front end elevational view on line 2—2 of Figure 1.

Figure 3 is a top plan view similar to Figure 1, except the cover plate member is shown swung open to allow the circular brim of the hat to be inserted and removed therefrom.

I claim:

The ornamental design for a flat brim holder for spiral stitching of hats, as shown and described.

ISIDORE KLAINBARD.
